US00D919948S

(12) **United States Design Patent** (10) **Patent No.:** **US D919,948 S**
Wira (45) **Date of Patent:** **** May 25, 2021**

(54) **SOLE FOR A SHOE**

(71) Applicant: **adidas AG**, Herzogenaurach (DE)

(72) Inventor: **Adrien Wira**, Les Baroches (FR)

(73) Assignee: **adidas AG**, Herzogenaurach (DE)

(**) Term: **15 Years**

(21) Appl. No.: **29/744,866**

(22) Filed: **Jul. 31, 2020**

Related U.S. Application Data

(63) Continuation of application No. 29/690,834, filed on May 10, 2019, now Pat. No. Des. 891,736, which is

(57) **CLAIM**

The ornamental design for a sole for a shoe, as shown and described.

DESCRIPTION

The FIGURE is a side view of a sole for a shoe showing the claimed design.

The broken lines in the FIGURE and the areas within the broken lines show environment and portions of the sole for a shoe that form no part of the claimed design.

1 Claim, 1 Drawing Sheet

Related U.S. Application Data

a continuation of application No. 29/610,313, filed on Jul. 11, 2017, now Pat. No. Des. 848,126.
